Primary Examiner — Cynthia Underwood(74) *Attorney, Agent, or Firm* — Mind Law Firm, P.C.; Justin G. Sanders; Jerome V. Sartain(57) **CLAIM**

The ornamental design for a protective case for a tablet computing device, as shown and described.

DESCRIPTION

FIG. 1 is a perspective view showing an exemplary embodiment of our new protective case for a tablet computing device design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines are included for illustrative purposes and form no part of the claimed design.
